UNITED STATES PATENT OFFICE

2,604,605

HIGH-FREQUENCY TUBE STRUCTURE

Sigurd F. Varian, Garden City, N. Y., assignor to
The Sperry Corporation, a corporation of Delaware

Original application January 29, 1942, Serial No.
428,682. Divided and this application Decem-
ber 14, 1946, Serial No. 716,209

25 Claims. (Cl. 315—5)

1

This invention relates, generally, to ultra-high-frequency vacuum tube structure; and, more specifically to ultra-high-frequency devices of the electron beam type such as disclosed in Patents No. 2,245,627, entitled "Stabilization of Frequency," issued June 17, 1941, in the name of Russell H. Varian, No. 2,250,511, entitled "Oscillator Stabilization System," issued July 29, 1941, in the names of Russell H. Varian and William W. Hansen and No. 2,259,690, entitled "High Frequency Radio Apparatus," issued October 21, 1941, in the names of John R. Woodyard, William W. Hansen and Russell H. Varian. The present application is a division of application Serial No. 428,682 filed January 29, 1942, issued as Patent No. 2,414,785 on January 21, 1947.

In the aforementioned disclosures, there is shown an ultra-high-frequency device consisting of an indirectly heated cathode which projects an electron beam through grids which form portions of the opposite walls of a hollow-cavity conducting resonator. After the electron beam leaves the exit grid of the resonator, it is reflected back through the resonator by means of a reflector electrode operating at or very near to the potential of the cathode. If a high frequency alternating electric field exists between the resonator grids due to the presence of a corresponding high frequency alternating electromagnetic field in the resonator, the electron beam suffers recurrent velocity changes by the action of said alternating electric field during its initial passage through the resonator. As the electron beam passes through the exit grid of the resonator and onward, the effect is to commence to produce recurrent grouping of the electron beam. The spacing between the resonator exit grid and the reflector electrode, and the voltage on said electrode, are so arranged that the electrons are reflected back into the resonator at a time when the recurrent velocity changes have resulted in recurrent grouping of the electron beam and at a time such that these electron groups return energy to the alternating electric field appearing between the resonator grids, thus maintaining the oscillating electromagnetic field inside of the resonator. Direct current energy is thus introduced into the device by means of the electron beam, and may be removed as ultra-high-frequency energy from the hollow resonator by means of coupling loops and associated concentric line elements, as more fully described in the aforementioned patents.

One object of the present invention is the provision of improved tuning means for high fre-

2

quency tube structures of the type employing a single resonator such as disclosed in the above-mentioned patents, together with suitable resonator, cathode, and reflector electrode shapes and structure for operating such devices at wavelengths on the order of ten centimeters or less.

A further object of the invention is to provide novel types of indirectly heated cathode structures suitable for use in the small spacings involved in short wavelength hollow-cavity resonant devices.

Another object is to provide temperature compensation of the frequency of such a device by suitable choice of materials and design.

15 Still another object is to provide such an ultra-high-frequency device with a resonator constructed so that desirable close spacing of resonator grids, cathode, and reflector plate may be achieved.

20 A further object is to provide mechanical tuning means whereby the grids of a single hollow cavity resonator electron beam velocity modulating device of the aforementioned type may be moved parallel to each other, thus maintaining parallelism of the cathode and reflector plate structures associated therewith.

Fig. 1 is a cross-sectional elevational view, of one form of tube structure according to one aspect of the present invention.

30 Fig. 2 is a fragmentary cross-section of a detail of Fig. 1, showing the cathode construction.

Fig. 3 is a perspective view of a modification of the structure shown in Fig. 2.

35 Fig. 4 is an alternate form of the structure of Fig. 2.

Fig. 5 is a partial cross-sectional elevational view of an alternate form of the structure shown in Fig. 1.

Fig. 7 is a fragmentary cross-sectional elevational view of an alternate form of the cathode structure shown in Fig. 5.

45 Fig. 8 is a partial cross-sectional elevational view of an alternate form of Figs. 1 and 5.

Fig. 9 is a modification of a detail of Fig. 8.

In Fig. 1 there is shown a single resonator electron beam velocity-modulation tube structure of the type disclosed in the aforementioned patents. Electrons from emitter 1 may be projected in a beam of round cross-section through entrance grid 8 of a hollow conducting resonator 9. Resonator 9, as shown, has a reentrant portion 10, a flexible end wall 11, an outer 50 cylindrical wall 12, and a rigid flat end wall 13.

opposite to wall 11. End wall 13 of resonator 9 is apertured and carries a grid structure 14 concentric with and close to grid 8. Grids 8 and 14 may, as shown in Fig. 5 of parent application 428,682, consist of an annular member provided with alternate long and short radial conducting bars inserted in rings which in turn are inserted in reentrant portion 10 and end wall 13. The elements of grids 8 and 14 may be made of zirconium or other metals which emit relatively few secondary electrons. Spaced concentric to grid 14 and close behind it is reflector electrode 18 which may be dish-shaped as shown. Reflector 18 is supported by conductor 19 which passes through glass end bell 20, which is in turn supported by and sealed to end wall 13 of resonator 9 in the conventional manner.

In operation, the electron beam emitted from cathode 1 is projected through entrance grid 8 into resonator 9. In this resonator the beam suffers recurrent velocity changes or is velocity-modulated by means of an oscillating electric field existing between grids 8 and 14. The beam travels out through exit grid 14 and is reflected back through grid 14 by a voltage applied to reflector 18 very near that of the cathode voltage, the reentry of the beam into resonator 9 taking place after recurrent bunching or density modulation of the beam has taken place, said grouped electron beam then giving up energy to the electric field between grids 14 and 8, thus maintaining oscillations in resonator 9.

Resonator 9 may be provided with coaxial line terminal posts or elements 21 and 22, emerging from resonator end wall 13, which may be similar in construction to that shown in Fig. 4 of the above-mentioned parent application.

For tuning resonator 9, flanges 29 and 30 are connected respectively to end plate 13 (and hence to grid 14) and to reentrant portion 10 (and hence to grid 8). A plurality of screws 37 are threaded into flange 29 in which are seated struts 61 whose other ends are seated in flange 30. In this way adjustment of screws 37 serves to adjust the spacing of grids 8 and 14 and hence tunes the resonator.

The tube structure shown in Fig. 1 has a low frequency shift with thermal changes and other advantages to be further explained. Frequency shift may be brought about from changes in the spacing between grids 8 and 14 due to thermal expansion or contraction. As will be apparent from a study of Fig. 1, such spacing change originates largely from two sources: expansion or contraction of the cylindrical portion 10 bearing entrance grid 8, and expansion or contraction of struts 61 and associated rough tuning screws 37. In Fig. 1, the reflex device has low thermal coefficient of frequency. Flanges 29 and 30 may be made of steel, or of other metal of low thermal conductivity, in order to avoid excessive temperature rise of the tuning mechanism thereto attached.

Reentrant portion 10 of resonator 9 continues beyond wall 11 and integrally flares out to flanged portion 60 parallel to flanges 29, 30, tube 10 being of one of the well known high nickel content alloys suitable for butt-sealing to certain glasses and having very low thermal coefficient of expansion and preferably having all of its surfaces inside of resonator 9 plated with copper or other highly conducting material. Flange 30 is attached directly to the extended portion of cylinder 10 between resonator 9 and flared portion 60. Struts 61 are of Invar or other material of

low thermal expansion coefficient, as are also screws 37 engaging these studs. Cathode 1, which may be of any of the types to be further described, is placed inside of reentrant portion 10, thus dispensing with an exit grid such as shown in Fig. 1 of the parent application, and may be supported in the conventional manner by leads projecting through glass press 63 sealed to cylindrical glass vacuum envelope 62 which, in turn, is butt-sealed near the periphery of flange 60.

Suitable cathodes for use in a tube of the type shown in Fig. 1 in which the cathode is mounted adjacent to entrance grid 8 and inside of reentrant tube portion 10 are shown in Figs. 2, 3, and 4. Because of small spaces available in reflex oscillators and amplifiers operating in the region below ten centimeter wavelengths, more conventional types of cathode structures as shown in parent Fig. 1 may not be desired. A structure which may be more readily adapted to such small spacings is shown in Fig. 2. Thermal conductive rod 74, as of tungsten or other material having a relatively high melting point, is positioned coaxially with the axis of the electron beam to be produced. A frustum 75 of a right circular cone has a small diameter end, of diameter substantially equal to that of conductor 74, welded or otherwise secured to the upper end of conductor 74. Frustum 75 may be of nickel or other heat-conducting material, and may have its large diameter surface coated with an oxide electron-emission material, as at 76. The cylindrical sides of rod 74 are coated with Al_2O_3 or other material of low electrical conductivity at high temperature, as at 87, and around said coating may be wound a coil 77 of heater resistance wire. The heater assembly is surrounded by heat shield 78, which may be a tube of nickel, and which positions the heater assembly by means to be described. Heat shield 78 may have inserted in its lower end a double wall bottom, such as formed by walls 79, 80. Heat shield 78 extends above emitter surface 76 a distance sufficient to give the resultant electron beam a slightly focused quality.

Conducting rod 74 has its lower end terminated in a cone 81, the apex of the cone being positioned by a dimple in heat shield wall 80. As a point contact only is thus made between rod 74 and end wall 80, very little heat transfer is allowed. The other degree of freedom of motion of the heater structure inside of shield 78 is removed by making the upper sharp edge of the frustum 75 fit into an annular concave groove 82 near the top of heat shield 78 and of substantially arcuate cross-section. Such construction results in a line contact, so that very small heat exchange is allowed between the frustum 75 and heat shield 78. One end of heater coil 77 may be spot welded to heat shield 78, as at 84, while the other end is insulated from heat shield 84 by passing out through holes in bottom walls 79, 80. Leads 83 attached to shield 78 pass through the glass press of the vacuum envelope of the tube and provide a rigid support for the cathode structure, and, together with lead 85, supply the necessary heater voltages.

It may be desirable to use a larger wattage heater coil in place of coil 77 of Fig. 2 in which case the structure of Fig. 4 may be used. The conducting member 74 is now extended well past flange 60 and is of diameter more nearly that of the inner diameter of heat shield 78. As it passes beyond flange 60, heat shield 78 is enlarged to fit a cylinder 86 which may also be of

nickel and which is closed at its lower end by end wall 88. The portion of conductor 74 covered with Al_2O_3 and surrounded by heater coil 89 may be equal in diameter to the remainder of rod 74, or may be of somewhat greater diameter, as desired, allowing coil 89 to be more easily assembled and to be of greater power capacity. It is to be understood that heater coils 77 and 89 may be of the coiled coil variety if desired, or may be any type of non-inductive winding.

If frustum 75 and heat shield 78 are both of nickel, welding may result due to the usual high operating temperature of such a cathode at the line contact between frustum 75 and annular groove 82, resulting in increased heat transfer between the cathode and heat shield. The structure of Fig. 3 may be used to remedy this undesired result. The larger diameter of the frustum 75 is made smaller than the inner diameter of heat shield 78 so that three wires 90, 90', 90'' of molybdenum or other suitable material may be inserted between the frustum and the heat shield. The wires 90, 90', 90'' may be held in position by pressure only or may be bent into slots 91, 91', 91'' cut into the upper face of heat shield 78, the material of the heat shield adjacent to the slots then being staked over to hold wires 90, 90', 90'' firmly in proper placement. The heater assembly may be held in position by a slant tension on lead wires 85, 85', of heater coil 89.

For much shorter output wavelengths, modification of the shape of the resonator may be useful in providing sufficient space for the cathode and the reflector electrode, as is shown in Fig. 5. Here resonator 92 is made by turning out of a round conducting disc a cavity having the shape of a frustum of a right circular cone, thereby forming an outer wall 93 and an upper apertured wall 94 which carries exit grid 95 of the resonator 92 (where such grid is used). A flexible conducting diaphragm 96 and reentrant apertured portion 97, which is also a frustum of a right circular cone, form the remainder of the resonator boundary. Reentrant portion 97 carries entrance grid 98 (when used) placed concentric with and close to exit grid 95.

Grids 95 and 98 may, as shown in Fig. 6, consist of radial conducting long and short wires 99 and 100. These grid wires may be inserted in wall 94 and reentrant member 97 by milling radial slots in the upper surfaces of 94 and 97, placing the grid wires in the slots in the correct positions, and exerting hydraulic pressure to those faces great enough to cause the surface metal to flow over the wires, thus staking them in position, or by any other method which will leave relatively smooth surfaces after the grids are inserted.

Outside of the resonator, reentrant portion 97 may be extended as a tube 101 and is provided with a flange 102 cooperating with a flange 103 attached to resonator body 93, said flanges being used with any desired mechanical tuning mechanism, such as that of parent Fig. 1. The emitter surface of cathode 104 is placed close to entrance grid 98, and well inside of tube 101. Cathode 104 may be similar to that shown in Figs. 2 to 4 or of the type shown in Fig. 7 yet to be described, and may be surrounded by a tubular focusing shield 105, which extends past emitter 104 toward grid 98, and which may be supplied with a voltage relative to cathode 104 sufficient to give slight convergence to the resultant electron beam. Focusing shield 105 is supported and supplied

with proper voltage by leads 106, which pass through glass press 107. Reflector plate 108 is shown as a flat disc with a short cylindrical wall or flange projecting toward exit grid 95 from the periphery of said disc.

Coupled with resonator 92 by coupling loop 109 is a coaxial line through which ultra-high-frequency energy may be removed, consisting of small diameter portion 110, tapered portion 111, and larger diameter portion 112 containing a glass seal 113 to provide continuity of the vacuum envelope. All three of the sections have the same inner and outer conductor diameter ratios at any given cross-section in order to avoid impedance discontinuities in the line. Tapered section 111 is provided so that portion 110 may be of small enough diameter to fit the small resonator 92 used. It is evident that any desired number of such coupling loops and concentric line terminal posts may be provided with any of the structures herein shown.

The modified form of cathode shown in Fig. 7 is adapted for use in structures such as that shown in Fig. 5. This cathode consists of a metal tube 114 which acts as a heat shield, projecting past emitter surface 115 to afford a slight focusing of the electron beam thereby produced, and containing heater coil 116. Emitter surface 115 is made very thin compared to the thickness of tube 114, and may be oxide coated. The cathode assembly is held rigidly by a truss system of wires 117 arranged in V-formations and supported upon the outer conductor 118 of a coaxial line having an inner conductor 119 that is sealed inside of tube 118 by glass to metal seal 120. The tubular outer conductor may be used as one lead to heater coil 116, while inner conductor 119 is used as the other lead to heater 116, the accelerating voltage being applied between 118 and 101.

It is found that for reflex devices of the above type, and especially for shorter wavelength tubes, it becomes desirable to maintain the resonator grids always parallel so that the associated cathode and reflector electrode structures remain in alignment. One form of structure for producing this result is shown in Fig. 8. In this device, resonator 135 is formed by a cylindrical outer wall 135, a rigid end wall 148 carrying a central exit grid 137, a flexible end wall 132, and a reentrant pole 136 carrying entrance grid 136'. Cathode 139 and reflector 140 are aligned with grids 136', 137 on opposite sides thereof.

Cylindrical outer wall 135 and reentrant tube 136 of the resonator 134 are considerably extended, and a second flexible diaphragm 138 is used to close the open end of tube 135. Pressure exerted by a tuning lever 43 of a mechanical tuning mechanism which may be similar to that of parent Fig. 1 forces tube 135 to always move parallel to tube 136, thus maintaining grids 136' and 137 parallel. This method of construction is seen to eliminate some of the complexity of the tuning device, and is seen to also be useful with two resonator electron beam devices.

To obtain perfect alignment of grids 136', 137, cathode 139, and reflector electrode 140, it may be desirable to provide adjustment means for positioning the cathode and reflector. Resonator 134 has its upper wall 148 extended to form flange 141. Mounted above wall 148 is tube 142 which carries in its open end apertured flexible diaphragm 143. Mounted in the central aperture of diaphragm 143 is tube 144 which is sealed to glass insulator 145 which supports conductor 149 on which reflector electrode 140 is mounted.

Tube 144 also carries flange 146, parallel to and spaced from flange 141. Three screws 147 are mounted at 120° intervals to rotate freely in holes near the periphery of upper flange 146. The other ends of screws 147 are threaded into flange 141, and thereby afford means of adjustment to secure parallelism between exit grid 137 and reflector 140 and the proper spacing of these elements.

Cathode 139, which is mounted on concentric line 150 which projects through glass insulator 151 in the manner described in connection with Fig. 7, and which extends up into the reentrant tube 136, may be similarly adjustably by the action of three spaced screws 152 cooperating with flanges 153 and 154 to cause motion of flexible diaphragm 155.

It may be desired to provide the flexible diaphragm means 143, 155 for preliminary adjustment of cathode and reflector spacings at the factory, also providing means to prevent possibility of misalignment at a future date. As seen in Fig. 9, in an illustration showing the method as used on the reflector end of the tube, flanges 141 and 146 and cooperating screws 147 of Fig. 8 are dispensed with. Tube 142 is made to extend well above flexible diaphragm 143, as at 157. After alignment of reflector plate 143 and grid 137, solder or other low melting alloy 156 may be poured into the volume defined by tube 157, diaphragm 143, and tube 144. After the alloy cools, the jig or other clamping device used in determining the optimum position of the reflector plate may be removed, the alloy thus securing the position of reflector 140. A similar procedure may be used in permanently positioning cathode 139 of Fig. 8.

Since many changes could be made in the above construction and many apparently widely different embodiments of this invention could be made without departure from the scope thereof, it is intended that all matter contained in the above description or shown in the accompanying drawings shall be interpreted as illustrative and not in a limiting sense.

I claim:

1. A high frequency tube structure comprising a cavity resonator having one wall thereof provided with a reentrant portion, said reentrant portion being apertured and being made of a high nickel content alloy having a low thermal coefficient of expansion, said resonator having an apertured wall portion opposite said reentrant portion, both of said apertures being aligned and forming an electron-permeable gap, a flexible diaphragm adjacent said reentrant portion, tuning means for varying the axial extent of said gap, said tuning means consisting in part of flanges connected to said reentrant portion and said apertured wall portion respectively, and a thermionic cathode structure contained at least partially within said reentrant portion for supplying electrons for passage through said gap.

2. A high frequency tube structure as defined in claim 1 wherein said cathode comprises a central rod having an enlarged head providing an electron emitting area, a heating coil surrounding said rod, and heat shielding means surrounding said heating coil, at least a portion of said heat shielding means projecting into the reentrant portion of said resonator wall.

3. A cathode structure comprising a central heat conducting rod having a pointed end portion and an enlarged end portion, a heating coil sur-

rounding said rod intermediate its end portions, and a heat shield surrounding said coil and projecting beyond said end portions, the portion of said heat shield projecting beyond the enlarged end portion of the rod constituting a focusing electrode.

4. A cathode structure as defined in claim 3 wherein the portion of said heat shield projecting beyond the pointed end of said rod is provided with an end wall abutting said pointed end portion, the enlarged end portion also having a bearing upon said heat shield thereby affixing said rod in place within said shield.

5. A cathode structure for high frequency tubes comprising an indirectly heated thermal conductor having an enlarged end portion, said end portion having an emitting area, a heat shield surrounding said thermal conductor in spaced relation therewith, said heat shield having a portion thereof projecting forwardly of said emitting area, said forwardly projecting portion serving as a focusing shield for electrons leaving said emitting area.

6. High frequency tube apparatus comprising an indirectly heated cathode element having an emitting area, a heat shield surrounding said emitting element in spaced relation therewith and having a portion thereof projecting forwardly of said emitting area, said forwardly projecting portion constituting a focusing shield for electrons leaving said emitting area, a hollow resonator having an apertured reentrant wall receiving a portion of said cathode structure, said resonator having an apertured wall opposite its reentrant wall, and a reflector electrode positioned exteriorly of said opposite apertured wall, said reflector electrode being formed with a peripheral focusing portion.

7. A cathode structure for ultra-high-frequency tubes comprising an inner heating coil, a cylindrical relatively thick tube surrounding said heating coil and constituting the exterior wall of said cathode structure and also a heat shield, and a relatively thin emitter plate contained within said tube near one end thereof and adjacent to said heating coil to be heated by the latter, a portion of said tube projecting forwardly of said emitter plate and serving as a focusing electrode.

8. A high frequency tube structure comprising a cavity resonator having one wall thereof provided with a reentrant portion, said reentrant portion being apertured, and a cathode structure contained at least partially within said reentrant portion for supplying electrons for passage through said resonator, said cathode structure comprising a central rod having an enlarged head providing an electron emitting area, a heating coil surrounding said rod, and heat shielding means surrounding said heating coil, at least a portion of said heat shielding means projecting into the reentrant portion of said resonator wall.

9. A cathode structure comprising a central heat conducting rod having an enlarged end provided with a thermionic emissive surface, a heating coil surrounding said rod and a heat shield surrounding said coil and extending beyond the ends of said rod, the portion of said heat shield projecting beyond the enlarged end portion of said rod serving as a focusing electrode.

10. High frequency apparatus comprising a cathode element having an emitting area, a heat shield surrounding said cathode element in spaced relation therewith and having a portion thereof projecting forwardly of said emitting

area, and constituting a focusing shield for said electrons leaving said emitting area, a hollow resonator having an apertured reentrant wall receiving at least a portion of said shield, said resonator having an apertured wall opposite said reentrant wall and a reflector electrode positioned exteriorly of said opposite apertured wall.

11. A cathode structure for ultra-high-frequency tubes comprising an inner heating coil, a relatively thick tube surrounding said heating coil and serving as the electron wall of said cathode structure and also as a heat shield, and an emitter element having low heat capacity contained within said tube near one end thereof and adjacent to said heating coil to be heated by the latter.

12. A high frequency tube structure comprising a resonator body provided with a resonator cavity having substantially the shape of a frustum of a cone, said resonator having a reentrant wall portion also of substantially frusto-conical shape, the inner end of said reentrant wall portion having an inner end apertured for the ingress of electrons into said resonator and being made of a high nickel content alloy having a low thermal coefficient of expansion, said resonator having an apertured wall portion opposite said reentrant portion, both of said apertures being aligned and forming an electron permeable gap, a flexible diaphragm adjacent said reentrant portion, tuning means for varying the axial extent of said gap, said tuning means consisting in part of flanges connected to said reentrant portion and said apertured wall portion respectively, and a thermionic cathode structure contained at least partially within said reentrant portion for supplying electrons for passage through said gap.

13. High frequency tube apparatus comprising a cavity resonator having a reentrant portion, said reentrant portion being formed as a part of a tube whose external end is flared in a plane substantially perpendicular to the axis of said tube, a vitreous press butted to said flared portion, and a thermionic cathode supported by said press and extending within said reentrant portion.

14. A high frequency tube structure comprising a cavity resonator having a copper outer wall and an inner reentrant portion, said resonator having a pair of aligned apertures defining an electron permeable gap, and an indirectly heated cathode located at least partly within said reentrant portion, the material of said reentrant portion having a low linear coefficient of thermal expansion, whereby variations in the axial spacing of said gap due to temperature-responsive changes in the linear extent of said reentrant portion resulting partially from the heat supplied to said cathode is minimized.

15. Apparatus as in claim 14 wherein the material of said reentrant portion is composed of a high nickel content alloy, said coefficient of thermal expansion being of the order of magnitude suitable for butt-sealing to glass.

16. High frequency tube apparatus comprising a cavity resonator having a first apertured end wall supporting a first grid, a centrally apertured flexible diaphragm providing a second end wall, and a reentrant portion including a cylindrical member extending through the aperture of said flexible diaphragm in the direction of said first wall and connected to said diaphragm, said reentrant portion having a second grid at one end thereof coaxial with and adjacent said first grid; a cathode coaxial with and located adja-

cent said second grid with at least a portion thereof contained within said reentrant portion; means for projecting an electron beam through said grids in a first traverse of said gap; means including a reflecting electrode positioned close behind said first grid for redirecting said electrons in a second traverse of said gap, said reflecting electrode being disc-shaped and having a flange at the periphery thereof axially extending in the direction of said cathode, whereby a close spacing of said cathode, said grids and said reflecting electrode is provided.

17. In high frequency tube apparatus, the combination comprising a cavity resonator having conductive internal surfaces and adapted to contain a cyclically-varying electromagnetic field, said resonator further having a reentrant portion extending axially of said resonator, said portion having a first grid located at one end thereof and being connected to a flexible diaphragm, said resonator also having a second apertured end wall having a second grid contained at least partially within said aperture, said grids being closely spaced from one another and defining an electron-permeable gap, a cathode located adjacent said first grid and at least partly contained within said reentrant portion, and a disc-shaped reflecting electrode positioned substantially close to said second grid and having a flange portion at the periphery thereof axially extending in the direction of said cathode, whereby close spacing of said first and second grids, said cathode and said reflecting electrode is provided.

18. A high frequency tube comprising an electron-emissive cathode electrode, means adjacent thereto for accelerating a beam of electrons from said cathode, a pair of control grids mounted in the path of said beam, and an additional electrode, said pair of control grids being adapted to be connected to a resonant circuit to impart velocity modulation to the electrons in said beam, one of said grids being spaced from the other of said grids by a substantial length of a metallic supporting member, said supporting member being made of a material having a very low thermal coefficient of expansion.

19. Apparatus as in claim 18 wherein the material of said supporting member is constituted of a high nickel content alloy.

20. A high frequency tube comprising an electron-emissive cathode, electrode means adjacent thereto for accelerating a beam of electrons from said cathode, a pair of control grids mounted in the path of said beam, and an additional electrode, said pair of control grids being adapted to be connected to a resonant circuit to impart velocity modulation to the electrons in said beam, one of said grids being spaced from the other of said grids by a substantial length of a metallic supporting member, said supporting member being made of a high nickel content alloy.

21. Apparatus as in claim 20 wherein the linear coefficient of thermal expansion of said supporting member is low, said coefficient of expansion being suitable for butt-sealing to glass.

22. An electronic discharge tube comprising an electron-emissive cathode electrode, and a pair of electrodes mounted adjacent thereto in the path of the electrons emitted from said cathode, one of said electrodes being spaced from the other of said electrodes by a substantial length of a metallic-supporting member, the operation of said tube being critically dependent on the spac-

ing between said electrodes, said supporting member being made of a material having a very low thermal coefficient of expansion.

23. Apparatus as in claim 22 wherein said supporting member is composed of a high nickel content alloy, said coefficient of expansion being of the order of magnitude suitable for sealing to glass. 5

24. A high frequency electron discharge device comprising an electron emissive surface, cavity resonator means having longitudinally spaced apertures, said apertures being substantially aligned with said surface to permit the passage of electrons therethrough, means for maintaining in the presence of temperature change the longitudinal spacing of said apertures substantially constant, said last-named means including a portion of said resonator means composed of a high nickel content alloy having a low thermal coefficient of expansion, said thermal coefficient being of the order of magnitude suitable for butt-sealing to glass. 10

25. A high frequency electron discharge device comprising an electron emitter, a cavity resonator having a reentrant portion with a first aperture at the end thereof, said resonator further having a second aperture registering with said first aperture, both of said apertures 15

being positioned to pass electrons emanating from said emitter, the spacing of said apertures being effective for regulating the resonant frequency of said resonator, means for maintaining despite temperature variations the spacing of said apertures substantially constant, said last-named means including a high nickel content alloy having a low thermal coefficient of expansion for a part of said reentrant portion. 20
